United States Patent Office.

WILLIAM G. TUTTLE, OF CHELSEA, MICHIGAN.

Design No. 4,009, dated May 3, 1870.

DESIGN FOR CROSS-CUT SAWs.

The Schedule referred to in these Letters Patent and making part of the same

To all whom it may concern:

Be it known that I, WILLIAM G. TUTTLE, of Chelsea, in the county of Washtenaw and State of Michigan, have invented or produced a certain new and original Design for Cross-Cut Saws, of which the following is a specification.

My invention is a design for cross-cut saw, as follows:

The back *b* is made concave or hollowing.

Handles *c* are to be secured to ends of the saw.

The cutting edge *a* is of usual form of convexity.

I thus produce a neat and useful design, and com-

bine therewith the advantage of lightness and strength, less material, and decrease of friction.

Having thus described my invention,

What I claim as new, and desire to secure by Letters Patent, is—

The design for cross-cut saws, as shown and described.

In witness whereof I have hereunto signed my name in the presence of two subscribing witnesses.

Witnesses: W. G. TUTTLE.

R. F. OSGOOD,
GEO. W. MIATT.
